BLADE SET FOR DENTAL INSTRUMENT

James Vannes Boone, Meadows Bldg.,
Dallas, Tex. 75206

Original design application Oct. 13, 1969, Ser. No. 19,514.
Divided and this application Apr. 1, 1971, Ser. No.
130,569

Term of patent 14 years

Int. Cl. D24—02
U.S. Cl. D24—1

FIG. 1

FIG. 2

FIG. 3

FIG. 4

FIG. 5

FIG. 6

FIG. 1 is a top plan view of a blade for a dental instrument showing my new design;

FIG. 2 is a bottom plan view thereof;

FIG. 3 is a side elevation thereof;

FIG. 4 is a top plan view of a modified embodiment of the blade illustrated in FIG. 1;

FIG. 5 is a bottom plan view thereof; and

FIG. 6 is a side elevation thereof.

This is a division of design application Ser. No. D. 19,514, filed Oct. 13, 1969, and now Pat. No. D. 221,855.

I claim:

The ornamental design of a blade set for dental instrument, as shown and described.
